UNITED STATES PATENT OFFICE.

LEON ALONZO WITTER, OF JACKSON, MICHIGAN, ASSIGNOR OF ONE-HALF TO GUSTAVE A. WEBER, OF JACKSON, MICHIGAN.

SPARK-PLUG.

1,221,940.

Specification of Letters Patent. Patented Apr. 10, 1917.

Application filed November 1, 1916. Serial No. 128,997.

To all whom it may concern:

Be it known that I, LEON ALONZO WITTER, a citizen of the United States, residing at Jackson, county of Jackson, State of Michigan, have invented a certain new and useful Improvement in Spark-Plugs, and declare the following to be a full, clear, and exact description of the same, such as will enable others skilled in the art to which it pertains to make and use the same, reference being had to the accompanying drawings, which form a part of this specification.

My invention relates to spark plugs for internal combustion engines and an object 15 of my improvements is to provide a spark plug in which the sparking point will not be bridged by deposits thereon.

In the accompanying drawing:

Figure 1 is an elevation of a conventional 20 spark plug partly broken away at the lower end showing the apparatus embodying my invention secured thereto.

Fig. 2 is an inverted plan view of the same.

Fig. 3 is a detail plan view of the shutter removed from its mounting.

a is the spark plug having the screw-threaded portion *b* in the usual and conventional form. *c* indicates the hollow in 30 the lower portion of the spark plug, and *d* is the central rod constituting one of the electrodes.

I drill a hole in the lower edge of the part *b* of the spark plug and in that I insert the end *e* of a wire and fix it therein. The wire *e* is then turned to a horizontal 35 position and extends in the part *f* which is parallel to the plane of the lower end of the plug and closely adjacent thereto.

Upon this portion *f* I pivot a shutter *h* which is provided with an eye *i* which engages over the portion *f*.

The rod *e f* is again turned at right angles and extends in the portion *g* below the shutter *h* so as to support the same in a position at which it is slightly away from the lower edge of the spark plug. There is a circular aperture *j* formed through the cen-

ter of the shutter *h*, and the walls of said aperture surround the electrode, at a proper 50 sparking distance from said electrode.

The shutter *h* is adapted to close against the lower end of the plug *a* and to separate the hollow *c* of said plug from the explosion chamber of the engine except for the 55 very small aperture *j*.

The operation of the above described device is as follows:

The shutter *h* is in electrical connection with the spark plug and therefore the spark 60 passes between the electrode *d* and the wall of the aperture *j*.

The shutter *h* will be kept in continual motion by the action of the gases in the 65 operation of the engine.

When compression takes place, or the explosion occurs, or the pressure in the cylinder increases in any way, the gases will seek to pass into the hollow *c* of the plug and in so doing will cause the shutter 70 *h* to close against the end of the plug. When the pressure in the cylinder lowers the gases will expand from the hollow *c* and assist gravity in carrying the shutter to the lower extremity of its travel where it is 75 held by the portion *g* of the wire *e f g*.

Thus should any foreign matter, such as water or soot, accumulate between the wall of the aperture *j* and the electrode *d*, the motion of the shutter *h* will throw it off and 80 it will not form a bridge between the electrode and interrupt the igniting spark.

What I claim is:

The combination with a spark plug provided with a hollow, an electrode concentric with said hollow, a movable electrode adapted to open and close said hollow and to be actuated by the gases in the cylinder, said second electrode being provided with an aperture surrounding said first electrode 85 and having its walls within sparking distance of the same.

In testimony whereof, I sign this specification.

LEON ALONZO WITTER.
